U.S. Appl. No. 29/496,023, filed Ju. 8, 2014, Thompson et al.

Primary Examiner — Terry Wallace(74) *Attorney, Agent, or Firm* — Wolf, Greenfield & Sacks, P.C.(57) **CLAIM**

The ornamental design for a beverage cartridge holder, as shown and described.

DESCRIPTION

FIG. 1 is a top, front, right perspective view of a beverage cartridge holder showing our new design;
FIG. 2 is a front elevational view thereof;
FIG. 3 is a rear elevational view thereof;
FIG. 4 is a right side elevational view thereof, the left side elevational view being a mirror image of FIG. 4;
FIG. 5 is a top plan view thereof; and,
FIG. 6 is a bottom plan view thereof.

The broken lines illustrate portions of the beverage cartridge holder that form no part of the claimed design. The dash-dot-dash lines define boundaries of the claimed design.
